VALVE

Raymond H. Leitzel, Forest Hills, Pa., assignor to
Westinghouse Electric Corporation, East Pittsburgh, Pa., a corporation of Pennsylvania

Application December 5, 1944, Serial No. 566,725

5 Claims. (Cl. 200—148)

1

This invention relates to circuit breaker apparatus, and more particularly to a blast valve mechanism and operating means therefor for a fluid pressure operated circuit breaker of the type in which a blast of compressed gas is employed for arc extinguishing purposes.

A form of fluid pressure operated circuit breaker that has been successfully employed under modern service conditions comprises a reservoir adapted to be charged with compressed air or other gas, a multi-pole arc extinguishing equipment supported above the reservoir and including suitable movable contact elements, fluid pressure operating means for opening and closing the circuit breaker, and a plurality of gas blast valve mechanisms interposed between the reservoir and the arc extinguishing apparatus, the blast valve mechanisms being simultaneously responsive to movement of the operating mechanism for controlling the flow of compressed air from the reservoir for extinguishing the arcs drawn in the separate pole units. Because of the fact that the blast valve mechanism for each pole of such a circuit breaker equipment is preferably adapted to form part of the supporting structure of the completed assembly, it is desirable to devise the individual blast valve devices and the operating mechanisms thereof in such a manner as to render the various elements readily accessible, and to facilitate removal of such parts of any blast valve device as may be necessary for inspection or repairs, without dismantling or in any way interfering with the supporting structure of the circuit breaker. It is also desirable to provide a blast valve assembly having a minimum number of relatively simple operating parts that can be manufactured and assembled at low cost, and which may be maintained through a long service life without the requirement of unduly frequent inspection, service and repair.

It is an object of my invention to provide an improved gas blast valve apparatus for a circuit breaker of the above class and incorporating the desirable features just mentioned.

Another object of my invention is the provision of a blast valve assembly for a circuit breaker comprising a casing adapted to be permanently built into the circuit breaker supporting structure, a valve body section removably mounted in the casing, and a blast valve and operating mechanism therefor operatively supported by the valve body section, the entire body section and valve mechanism being removable from the casing as a unit.

A further object of my invention is the provi-

2

sion of an improved blast valve mechanism for a multi-pole circuit breaker including actuating lever means for controlling operation of the blast valve in accordance with operation of a cam carried by the main operating shaft of the circuit breaker, and means for adjusting the cam to insure operation of the associated blast valve with relation to operation of the other blast valve mechanisms of the circuit breaker.

10 Other objects and advantages of the invention will appear in the following more detailed description thereof, taken in connection with the accompanying drawings, in which:

15 Figure 1 is an elevational view, partly in section, of one end of a multi-pole circuit breaker of the fluid pressure operated gas blast type in which each pole unit, one of which is illustrated, has a blast valve assembly constructed in accordance with my invention.

20 Fig. 2 is an enlarged detail sectional view of the blast valve mechanism shown in Fig. 1, and

Fig. 3 is an end view of the valve operating mechanism taken substantially along the line III—III of Fig. 2.

25 As shown in Fig. 1 of the drawings, a circuit breaker with which my improved blast valve mechanism is adapted to be employed may comprise a base 10, a compressed air reservoir 11 supported thereon and having a plurality of bolting

30 flanges 12, on each of which is mounted a blast valve casing 13 that may be bolted or otherwise secured thereto. On each blast valve casing 13 is mounted a substantially vertically disposed blast conduit 14 of insulating material, at the

35 upper end of which is supported an arc extinguishing structure 15. In addition to the support afforded by the several conduits 14, the arc extinguishing structures 15 are further supported on a framework including a plurality of insulating members 16 and bracket portions 17 projecting

40 from the reservoir 11. The arc extinguishing structure 15 is shown in fragmentary form in the drawings, but will be understood to carry a suitable terminal element 20 for the corresponding pole of the circuit breaker, to which is connected a stationary contact element 21. Journalled on pins 23 carried by the frame sections 24 of the respective pole units are movable contact elements 25, each of which is of curved formation and

45 adapted for movement into and out of engagement with the corresponding stationary contact elements 21 of the respective pole units. A suitable conductor and terminal member 26 is connected to each of the contact elements 25 to complete a circuit which, when the breaker contacts

55

are in circuit closed position, thus extends from the terminal 20 through the contact elements 21 and 25 to the terminal 26.

For operating the several movable contact elements, there is provided a single fluid pressure responsive mechanism 29 comprising a cylinder 30 in which is mounted a suitable piston, not shown, that is operatively connected through the medium of a piston rod 31 and links 32 to a crank arm 33 carried by a shaft 34. The shaft 34 is suitably journaled on bracket members 35 secured to the reservoir 11, and carries a plurality of upwardly extending lever or crank portions 37, each of the lever portions being aligned with one of the movable contact elements 25 and operatively connected thereto by means of an operating rod 39 formed of insulating material. Suitable means, not shown, is provided for initiating operation of the fluid pressure responsive mechanism 29.

Each of the blast valve casing sections 13 is adapted to be fitted with a suitable blast valve assembly which may be more readily understood by reference to Figs. 2 and 3 of the drawings. The casing 13 has formed therein an inlet passage 40 which communicates with the reservoir 11, and a discharge passage 41 communicating with the blast conduit 14, the lower end of which is adapted to rest on a bevelled surface 44 formed on the upper end of the casing. For securing the lower end of the conduit 14 in place, there may be provided a split ring 45 which is held in engagement with the blast conduit by means of an annular element 46 that is, in turn, secured in place by means of a plurality of bolts 47 having screw-threaded connection with the upper end of the casing 13. The casing 13 also has formed therein a bore 50 which is inclined at an angle with respect to the vertical axis of the casing, as shown in Fig. 2, and into which is snugly fitted a valve body section 51. Suitable means, such as bolts 52 indicated in Fig. 3, may be provided for securing the valve body section 51 to the casing 13. The body section 51 is provided with a passageway 41a which registers with the discharge passage 41 of casing 13 when the two parts are assembled. An annular valve seat element 54 is interposed between the lower end of the valve body section 51 and a flange 55 formed on the interior surface of the casing 13, a suitable gasket 56 being provided for insuring a leak-tight joint. Disposed in the inlet passage 40 is a blast valve element 57 which is adapted to engage a valve seat 58 formed on the seat member 54 for controlling flow of compressed gas from the reservoir 11 through the passage 41 to the blast conduit 14. The valve element 57 is carried on a plunger 60 which is slidably mounted in a suitable bore extending through the body section 51, the outer end of the plunger having screw threaded connection with a collar member 63 which is also slidably mounted with respect to the body section. A coil spring 64 is interposed between the collar 63 and a suitable wall on the body section for urging the valve element 57 upwardly and into seating engagement with the seat 58. An adjustable member 66 is secured to the outer end of the plunger 60. As may best be seen in Fig. 3, the adjustable member 66 is suitably bifurcated to provide legs 67 having threaded openings through which is screwed a bolt 68 to enable tightening of the element 66 into its proper position on the plunger.

It will be understood that the valve element 57 and other associated elements of the appara-

tus, including the plunger 60, are operatively aligned with the corresponding crank arm 37 carried by the operating shaft 34 of the circuit breaker. According to the invention, each crank arm 37 is equipped with an adjustable cam member 70 which is secured thereto by means of a pair of bolts 71 fitted into suitable slots (not shown) formed in the crank arm. The engaging surfaces of the cam member 70 and of the crank arm 37 are preferably provided with interlocking serrations, not shown in the drawings, to insure a rigid connection of the cam to the associated arm. Also, carried on the cam member 70 is a laterally projecting pin 73 which, for a purpose hereinafter explained, is disposed adjacent a cam surface 74 formed on the cam member.

On the outer end of the body section 51 are formed a pair of lugs 75 having suitable apertures for receiving a transversely disposed pin 76 on which are pivotally mounted the parallel intermediate legs of a bifurcated lever 78, the upper end of which, as viewed in Fig. 2, is also provided with parallel portions 78a which are adapted to straddle the element 66. The parallel portions 78a carry a transversely disposed pin 80, on which is journaled a roller 81 that is engageable with the element 66 carried by the plunger. The parallel leg portions of the lever 78 adjacent and below the pin 76, as viewed in Fig. 2, each terminate in a wing portion 78c in which is provided a screw-threaded bore for receiving a stop bolt 82. The stop bolts 82 are adapted for adjustment to permit engagement thereof with a surface 83 provided on the body section 51, to limit counterclockwise rotation of the lever 78 about the pin 76. The lever 78 substantially constitutes a bell crank lever and in addition to the parallel ends 78a is provided with parallel ends 78b, which extend outwardly and carry a transversely disposed pin 85 on which is pivotally mounted a second lever or pawl element 86.

The pawl element 86 has an end portion 86a adapted for engagement with the adjacent face of the lever 78, intermediate the pins 76 and 80, under the force exerted by a coil spring 88 which is interposed between a pin 89 secured to the lever 78 and a guide stem 90 pivotally connected to the pawl 86 by means of a pin 91. As viewed in Fig. 2 of the drawings, it will be seen that the spring 88 is thus adapted to urge pawl 86 toward its normal position and in a clockwise direction with respect to the pin 85 pivoting the pawl element to the bell crank lever 78. The end of the lever 86 opposite the end 86a is bifurcated to form a pair of legs 86b, which are adapted to straddle a roller 93 journaled on a pin 94. The roller 93 is adapted for engagement with the cam surface 74 of the cam element 70 during operation of the circuit breaker, as hereinafter explained. Also formed on the legs 86b are a pair of angularly disposed bearing surfaces 95 and 96 with which the pin 73 carried by the cam element is adapted to engage during operation of the mechanism.

In Figs. 1 and 2 of the drawings, the operating parts of the circuit breaker are illustrated as disposed in contact closed position, with the blast valve element 57 held in seated position under the force exerted by the spring 64 and by the pressure of air in the reservoir 11. When the usual circuit breaker control system is rendered operative to effect supply of air from the reservoir 11 to the piston within the cylinder 30 to effect a circuit opening operation of the circuit breaker, the piston rod 31 is moved downwardly and through the medium of the link elements 32

pulls the lever 33 downwardly turning shaft 34 and each of the crank arms 37 in a counterclockwise direction, as viewed in Fig. 1. It will readily be understood that this operation of the shaft 34 and crank arm 37 pulls the rod 39 downwardly to rotate the movable contact elements 25 out of engagement with the respective stationary contact elements 21, the movable contact elements rotating about pins 23. At the same time, as may best be understood by reference to Fig. 2, counterclockwise rotation of the shaft 34 and crank arm 37 brings the cam surface 74 of cam 70 into engagement with the roller 93 carried by the pawl element 86. As the cam element 70 is thus moved upwardly against the roller 93, it thereby turns the interlocked pawl element and lever 78 in a clockwise direction about the pin 76, thus forcing the roller 81 inwardly for operating the member 66 and plunger 60 to unseat the valve element 57. It will be understood that the force thus applied through the medium of the interlocked pawl element 86 and lever 78 to the plunger 60 for unseating the valve element is sufficient to overcome the combined pressures of the spring 64 and of air in the passageway 40. Upon unseating of the valve element 57 air under pressure is at once supplied from the reservoir 11 to the passageway 40, past the unseated valve element, and through passage 41 and blast conduit 14 for extinguishing the arc drawn between the separating contact elements of the associated pole unit of the circuit breaker.

The extent of movement of the valve element 57 during an unseating operation, as just explained, may be predetermined by the position in which the element 66 has been locked on the end of the plunger 60. The proper clearance initially provided between the roller 81 and the outer surface of the element 66 may also be predetermined by adjustment of the bolts 82.

Continued counterclockwise movement of the cam element 70 finally carries the highest portion of the cam surface 74 past the roller 93, whereupon the spring 64 is rendered effective to shift the plunger 60 outwardly to move the valve element 57 toward the seat 58, while moving the interlocked lever 78 and pawl element 86 in a counterclockwise direction with respect to pin 76. The valve element 57 is thus returned to its seated position for cutting off further flow of compressed air to the blast conduit 14 while the lever 78 and pawl element 86 are permitted to return to their normal positions, as indicated in Fig. 2, the bolts 82 being again disposed in engagement with the surfaces 83 of the body section 51. By this time the associated movable contact element of the circuit breaker has been shifted to its full circuit opening position and the arc has been extinguished.

Closing operation of the circuit breaker is effected by upward movement of the piston and piston rod 31 of the fluid pressure operating mechanism in the usual manner, this upward movement of the piston rod being effective through the medium of the links 32 and lever arm 33 to rotate the shaft 34 and crank arms 37 in a clockwise direction. Each crank arm 37 thus forces the associated rod 39 and movable contact element 25 upwardly until the contact element is brought into circuit closing engagement with the stationary contact element 21.

Meanwhile upon initial clockwise rotation of the shaft 34 and crank arm 37, as shown in Fig. 2, in effecting closure of the circuit breaker, the cam surface 74 of the cam element 70 is brought

into engagement with the roller 93 carried by the pawl element 86 and causes the latter element to rotate in a counterclockwise direction about the pin 85, overcoming the opposing force of the spring 88. During this operation of the pawl element, it will be understood that the bell crank lever 78 remains stationary in the position indicated in Fig. 2. Further movement of the cam element 70 by the rotation of the shaft 34 in a clockwise direction, as just explained, then effects engagement of the pin 73 with the bearing surface 95 of the pawl element, which continues to rotate about the pin 85 until the bearing surface 96 is permitted to slip into engagement with the pin 73.

If the circuit breaker is being closed to complete a circuit in which no fault is present, it is to be expected that the shaft 34, crank arm 37 and cam member 70 will then continue to move back to the normal position, as shown in Fig. 2, thus releasing the pawl element 86 and permitting it to return to the position shown in the drawings. If the circuit breaker is closed on a fault, i. e., during existence of an overload condition in the external circuit, however, the contact opening mechanism of the circuit breaker will be tripped in the usual manner before the operating elements have had time to bring the movable contact elements to their fully closed positions, whereupon the circuit breaker operating mechanism will be again actuated to initiate another circuit opening operation. The parts of the blast valve mechanism, as shown in Fig. 2, are so proportioned and arranged that the positioning of the pin 73 carried by the cam element 70 in engagement with the bearing surface 96 of the pawl element 86 during clockwise rotation of the shaft 34 as just explained, will occur at substantially the same time as the circuit breaker trip mechanism is adapted to respond to an overload condition or fault for operating the breaker to reopen the circuit. In a reopening operation the shaft 34, crank arm 37 and cam member 70 are again moved in a counterclockwise direction, and the pin 73 is thereby forced upwardly against the pawl element 86. Since the pawl element is at this time positioned to direct the upward force exerted through the medium of the pin 73 against the pin 85, it will be apparent that the bell crank lever 78 will thereby be operated in a clockwise direction about the pin 76 to reopen the valve element 57. When the cam element 70 has been carried far enough to disengage the pin 73 from the surface 96, the pawl element 86 is again permitted to return to its normal position with respect to the lever 78, while the latter element, together with the valve element 57 and plunger 60, are returned to their normal positions, as shown in Fig. 2, under the force exerted by spring 64.

It will thus be seen that I have provided a gas blast valve and operating mechanism therefor which is operative to supply a blast of compressed air during a normal opening operation of the circuit breaker, together with means preventing operation of the blast valve while the circuit breaker is operated to its closed position unless a reopening operation is effected before the breaker operating parts have regained circuit closed position, in which case the blast valve can again be actuated in the manner hereinbefore set forth.

The construction and arrangement of the elements of the blast valve mechanism embodying my invention is such as to facilitate removal of

the entire mechanism for inspection and renewal of parts without in any way interfering with the circuit breaker structure as a whole. Thus by removing the bolts 52 (see Fig. 3), the body section 51, together with the valve element 51 and the actuating elements 86 and 78, may be withdrawn from the casing 13 as a unit, it being understood, of course, that the crank arm 31 will first be disconnectedly moved out of the way. In removing the valve assembly, the casing 13 need not be disturbed. With the valve assembly thus free of the casing, the seat element 54 may be renewed or reconditioned if desired, and the other elements similarly serviced, and after being reassembled, the unit can readily be reinstalled in the casing to condition the circuit breaker for further operation. It will be noted that the advantages inherent in the construction of the blast valve assembly in accordance with my invention are attained with a minimum number of easily adjusted parts, which although designed to provide adequate strength and endurance under severe operating conditions may nevertheless be manufactured and assembled at moderate cost.

Having now described my invention, what I claim as new and desire to secure by Letters Patent, is:

1. In a circuit breaker of the gas blast type having an operating mechanism including a rotary member movable during contact opening and contact closing operations of the circuit breaker, a blast valve assemblage therefor comprising a casing structure having fluid inlet and discharge passages, normally closed valve means operatively mounted in said casing structure for controlling communication from said inlet passage to said discharge passage, a cam member adjustably mounted on said rotary member, a bell crank lever journalled on said casing structure and having one end operatively associated with said valve means, adjusting means associated with said valve means and said bell-crank lever for determining the amount of opening movement of said valve means, a pawl member operatively connected to the other end of said bell crank for engagement by said adjustable cam member, said pawl member being interlocked with said bell crank for actuating said valve means in response to movement of said cam member during a normal opening operation of the circuit breaker, yieldable means permitting movement of said pawl to a non-operative position relative to said bell crank during normal closing operation of the circuit breaker, and auxiliary operating means carried by said adjustable cam member for limited operative engagement with said pawl member prior to return thereof from said non-operative position, whereby repeated operation of said valve means is insured in the event of sudden reopening operation of the circuit breaker from a partially closed position, and means for adjusting said adjustable cam and said auxiliary operating means relative to said rotary member to determine the time the valve will open during a normal opening operation and also during a reopening operation.

2. In a circuit breaker of the gas blast type having an operating mechanism including a rotary member movable during contact opening and contact closing operations of the circuit breaker, a blast valve assemblage therefor comprising a casing structure having fluid inlet and discharge passages, normally closed valve means operatively mounted in said casing for controlling communication from said inlet passage to said

discharge passage, retractile lever means operatively connected to said valve means, said lever means having an operative position for cooperation with said rotary means to actuate said valve means during a normal contact opening operation of the circuit breaker, means permitting yielding of said lever means to a retracted position to prevent operation of said valve means by said rotary member during contact closing operation, means for rendering said lever means operative in the retracted position to actuate said valve means in response to a reopening operation of the circuit breaker from a partially closed position, and means for adjusting the last mentioned means and said rotary means for coordinating operation of said valve means with operation of the other elements of said circuit breaker.

3. In a circuit breaker of the gas blast type having an operating mechanism comprising a rotary member movable during contact opening and contact closing operations of the circuit breaker, a blast valve assemblage for said circuit breaker comprising a casing structure having fluid inlet and discharge passages, normally closed valve means mounted in said casing structure for controlling communication from said inlet passage to said discharge passage, a bell crank pivotally mounted on said casing structure, means on one arm of said bell crank engageable with said valve means to open said valve means, a lever pivotally mounted on the other arm of said bell crank for unitary movement therewith in one direction, spring means normally biasing one end of said lever into engagement with said one arm of said bell crank, a cam carried by said rotary member for engaging the other end of said lever and actuating said lever and said bell crank in one direction to effect opening of said valve means, adjusting means for adjusting said cam relative to said rotary member to vary the time said valve means will be opening during a contact opening operation, and adjusting means for varying the extent of opening movement of said valve means.

4. In a circuit interrupter of the gas blast type having an operating mechanism including a rotary member movable during contact opening and contact closing operations of said circuit breaker, a blast valve assemblage therefore comprising a casing structure having fluid inlet and discharge passages, a valve carrier body removably mounted in said casing structure, a normally closed valve means operatively mounted in said carrier body for controlling communication from said inlet passage to said discharge passage, retractile lever means pivotally mounted on said valve carrier body and operatively connected to said valve means, said lever means having an operative position for cooperating with said rotary means to actuate said valve means during normal contact opening operation of said circuit breaker, means permitting yielding of said lever means to a retracted position to prevent operation of said valve means by said rotary member during contact closing operation, means for rendering said lever means operative in the retracted position to actuate said valve means in response to reopening operation of the circuit breaker from a partially closed position, adjusting means cooperating with said lever means and with said valve carrier body for varying the position of said lever means relative to said valve means, and means for adjusting said rotary means for coordinating operation of said valve

means with the operation of the other elements of the circuit breaker.

5. In a circuit interrupter of the gas blast type having an operating mechanism comprising a rotary member movable during contact opening and contact closing operations of the circuit interrupter, a blast valve assemblage for said circuit interrupter comprising a casing structure having fluid inlet and discharge passages, a valve carrier removably mounted in said casing structure, normally closed valve means mounted in said carrier for controlling communication from said inlet passage to said discharge passage, a bell crank pivotally mounted on said valve carrier, means on one arm of said bell crank engageable with said valve means to open said valve means, a lever pivotally mounted on the other arm of said bell crank for unitary movement therewith in one direction, spring means normally biasing one end of said lever into engagement with said one arm of said bell crank, a cam carried by said rotary member for engaging the other end of said lever to actuate said lever and said bell crank in

5

10

one direction to effect opening of said valve means, adjusting means for adjusting said cam relative to said rotary member to vary the time said valve means will be opened during a contact opening operation, and adjusting means co-operating with said bell crank and with said valve carrier for adjusting the position of said bell crank relative to said valve means.
